UNITED STATES PATENT OFFICE.

SVEN GUNNAR NORDENGREN, OF LANDSKRONA, SWEDEN.

DIGGING MACHINE.

Application filed January 19, 1924. Serial No. 687,393.

To all whom it may concern:

Be it known that I, SVEN GUNNAR NORDENGREN, a subject of the King of Sweden, residing at Landskrona, Sweden, have invented certain new and useful Improvements in Digging Machines, of which the following is a specification.

The object of the invention is the provision of a digging machine which, besides being serviceable in such cases where a digging machine is generally used, is specially adapted for digging out goods or products kept in store buildings.

A further object of the invention is the provision of a digging machine of the endless conveyor type having an adjustable frame.

Another object of the invention is the provision of a pivoted extensible frame for the conveyor with means for automatically counterbalancing the combined weight of the frame and conveyor in any position.

Still another object of the invention is the provision of a conveyor frame adapted for adjustment to any fixed position in a vertical plane.

Other objects and advantages of the invention will appear in the following description, reference being had to the accompanying drawings.

In the drawings:

Fig. 1 is an elevation of the machine, and Figs. 2-6 are diagrammatic views showing several ways of using the machine, Fig. 3 specially illustrating the operation of the machine in columned store buildings.

In Fig. 1, the horizontal shaft through A, is fastened with bearings to a movable stand 1 and carries a polygonal frame ABCD, the rigid members 2, 3, 4 and 5 of which are movably joined together at the corners. Rotatably mounted in these corners are wheels carrying endless chains 6 to which digging tools 7 are secured.

When the machine is to be made ready for operation, the polygonal frame ABCD is placed in such a position as to cause the digging tools to properly engage the material to be dug out. The form of the frame is then securely fixed, and the stand is moved at a uniform rate of speed along the pile of the material. In digging out a suitable quantity in this way, the digging-tools are lowered into the pile and the stand is moved in the opposite direction.

According to the condition of the material operated on, the frame is placed in different positions. For material such as superphosphate that does not form a constant angle with the level, the frame is fixed in such positions that an inclination is obtained having a smaller angle to the level than the smallest angle possible, if the goods is to preserve its inclination without the risk of sliding down. The incline can be made plane, as the point C can be made to describe a straight line in the plane of the polygon (Fig. 1). The incline is altered by changing the angle BAD (Figs. 4 and 5).

For goods forming a constant angle with the level, the machine is operated in the manner shown in Figures 6 and 2, those positions being respectively the first and the last ones after and before the moving of the stand in the direction of the pile.

The said alterations of the frame may be effected manually if the polygon ABCD is balanced in a suitable way. For this purpose, the sides 2 and 4 of the frame ABCD may be lengthened with the parts 14 and 15, having their ends B¹ and D¹ movably joined together with two other parts 8 and 9 respectively (Fig. 1), the latter parts being likewise movably joined as at C¹ and carrying a balance weight 10. If the polygon A B¹ C¹ D¹ is made equiform to the polygon ABCD, the weight of ABCD may be balanced in all positions by the weight fixed at C¹. The only work required for the alteration of the frame is that which is called for to overcome the friction in the corners.

The polygonal frame ABCD is preferably made quadrangular with all sides of the same length or AB=AD and BC=DC. If the goods are pulverulent or granular, buckets may be used as digging-tools.

In order to prevent spilling of the goods from the parts AB and BC, the latter may be provided with chutes 11, in which the material is transported, the digging-tools serving as transporting means. On the material having been transported to A, the same will fall down into a hopper 12 after having first passed, if desired, through a pulverizing device 16 provided with a sieve or not, as required, and from the said hopper the material is further passed to barrows or bags 13.

If the position of the digging-tools is

to be brought about manually, the machine will require only a simple construction, the only parts demanding machine power being the movements to and fro of the stand and 5 the movement of the chains. A considerable quantity may be dug out without the necessity of shifting the stand in the direction of the pile (Figs. 4 and 5).

The construction is specially adapted to 10 stores built with columns. The machine is to be placed in such positions that the stand may be moved between the columns, the frames carrying the digging-tools having to be turned back when passing a column 15 (Fig. 3).

If required, the frame can be made revolving in the horizontal as well as in the vertical plane.

With the construction described above, 20 the counterweight 10 counterbalances the combined weight of the polygonal frame ABCD and the endless conveyor 6 carried thereby in all positions of adjustment since the frame members 2 and 4 are operative 25 through the extension members 14 and 15 to change the length of the moment arm of counterweight 10 in proportion to variations in the center of gravity of the polygonal frame in all positions of adjustment about 30 the center of support A.

The invention is susceptible of various changes in its form, proportions and minor details of construction and the right is herein reserved to make such changes as properly fall within the scope of the appended claims. 35

What I claim as new and desire to secure by Letters Patent of the United States of America is:—

1. A digging machine comprising an endless chain, digging tools fixed on said chain, an extensible frame supporting said chain, said frame being of polygonal form and comprising rigid frame members pivotally connected with each other, a stand pivotally supporting the frame, and means carried 45 by the frame for automatically maintaining

it in stable equilibrium on the stand in all positions of adjustment.

2. In a device of the class described, a polygonal frame comprising pivotally connected extensible members, means for supporting said frame from one of said pivotal connections, an endless carrier rotatably mounted on the frame, and means carried by the frame for automatically maintaining 50 said frame and carrier in stable equilibrium on said supporting means in all positions of adjustment.

3. In a device of the class described, a support, a frame member pivotally mounted 60 intermediate its ends on said support, a second frame member similarly mounted on the same axis, said members being independently movable in substantially the same vertical plane, pairs of link members pivoted 65 at one end to adjacent ends of said frame members and at the other end to each other, an endless carrier operatively carried by the members on one side of said support and a counterweight carried by the members on 70 the other side of said support.

4. In a digging machine, a support, an extensible frame pivoted to the support, excavating means supported by said frame, and means carried by said frame for automatically maintaining 75 said frame and means in stable equilibrium.

5. In a digging machine, a support, an excavator of the endless carrier type journaled on said support and free to move 80 in a vertical plane, means for manually varying the inclination of the work engaging portion of the carrier, and means carried by said means for automatically compensating for variations in the moment arm 85 of said excavator.

In testimony whereof I affix my signature in presence of two witnesses.

SVEN GUNNAR NORDENGREN.
